MECHANICAL RESUSCITATOR FOR
COMBATING ASPHYXIAHorace H. Raymond, Berlin, Conn., assignor to
William H. Stephenson, New York, N. Y.

Application April 26, 1939, Serial No. 270,216

13 Claims. (Cl. 128—30)

This invention relates to improved apparatus for providing mechanical resuscitation in cases of asphyxia.

Asphyxiation occurs upon the failure of either cardiac or respiratory action. It has been found, that life continues in human beings and the higher animals so long as the exchange of oxygen and carbon dioxide is continued in a normal way in the blood and tissues of the body. Ventilation of the body through the lungs serves to maintain oxygen and carbon dioxide in the tissues in proportion to their metabolic needs. Cardiac action through the circulating blood accomplishes the supply of oxygen to, and the removal of carbon dioxide from, the tissues of the body. Circulation and respiration are thus interdependent and both are regulated by the gas pressure of oxygen and carbon dioxide in the tissues of the body, and respiration and circulation in turn serve during life to maintain the gas pressures in the tissues substantially constant in each part of the body.

The reserve supply of oxygen in the human body is very limited, being sufficient to maintain life for only a few minutes when all supply from the outside is cut off. Many kinds of illnesses greatly increase the speed with which fatal asphyxia may develop and it is thus most important in severe cases of asphyxia that prompt treatment be begun as speedily as possible to restore and maintain the proper pressure of oxygen in the patient's body. While the patient is still breathing, manual resuscitation by exerting pressure rhythmically on the patient's chest is possible. In more advanced stages when the patient has become flaccid, the lungs are collapsed in the position of extreme expiration and the patient's body lacks sufficient elasticity for inhalations to be produced by the manual method. It is therefore necessary to expand and deflate the lungs in a positive manner. This may be done by the operator placing his mouth over the patient's mouth and by means of his own breath rhythmically forcing air into the patient's lungs and sucking it out. This mouth to mouth insufflation method has long been known and practiced but is subject to definite limitations. In the first place, it is possible to exert too much pressure, thus doing damage to the alveoli, especially in the case of premature infants. In the second place, it is impossible to maintain such treatment for long, especially in cases with anaerobic suppuration of the lung because of the fetor; and in the third place, it has the disadvantage that the op-

erator and/or patient, may be exposed to a grave risk of infection and of contracting disease.

Heretofore, complicated and expensive apparatus has been proposed for mechanical resuscitation. It is an object of my invention to provide an improved, simple and dependable apparatus to produce artificial respiration by means of mechanically induced inhalations and exhalations; another object of my invention is to provide such a device in such compact form that it may be kept available for emergency use without taking up more than a minimum amount of space; another object is to provide a device in which the positive and the somewhat lesser negative pressures created in the patient's lungs are accurately controlled and limited; a further object of my invention is to provide a device having means for mixing air with the oxygen supplied to the patient, and one which can be quickly converted from a resuscitator into an inhalator, or vice versa.

The term "oxygen" is used herein broadly to include not only 100% oxygen but any gas or mixture of gases for insufflating a patient's lungs or combating asphyxia. The invention will best be understood if the following description is read in connection with the accompanying drawing, in which

Figure 1 is a front view of my apparatus largely in cross-section;

Figure 2 is a front elevational view of my device;

Figure 3 is a detail sectional view of valve means for converting the device from a resuscitator to a simple inhalator, taken to the rear of the section of the valve shown in Figure 1;

Figure 4 is a sectional view taken longitudinally along the line 4—4 through the valve means shown in Fig. 3.

Figure 5 is a detail view largely in cross-section indicating the flow of gases in the apparatus during inhalation;

Figure 6 is a detail view largely in cross-section indicating the flow of gases in the apparatus during exhalation; and

Figure 7 is a detail sectional view taken at line 7—7 of Fig. 2 illustrating the crank connection pin in the inactive position.

The numeral 10 indicates the body portion of a device embodying my invention and has therein inhalation passageway 11 and exhalation passageway 12 which at its top communicates with the passageway 11 intermediate its ends. Each of the passageways 11 and 12 is provided at the lower end with screw threaded sockets 13 and 14

to receive the ends of conduits 13' and 14' for communication with a patient's respiratory system, preferably through a mask M, (see Fig. 2) which is placed over the patient's mouth and nose, and has a mouth piece, as will be well understood by those skilled in this art.

At its upper end the inhalation passage 11 has a socket 15 for connection to a pressure reducing unit identified in the drawing as "P. R. Unit" of an oxygen tank shown in Fig. 1 or to an intermediate tube or hose. A high speed nozzle 16 having a bore of very small diameter is provided in inhalation passageway 11 to increase the speed of flow of the oxygen therein, thereby creating suction in the exhalation passageway 12, which opens into passage 11 adjacent the ejection end of the nozzle 16, through portal S. As shown in Figure 1, a plug 15' is threaded in the top of the device in alignment with said nozzle to permit insertion and removal of the nozzle. Extending from adjacent the oxygen inlet coupling 15 around nozzle 16 is an inhalation by-pass 17 which also opens into inhalation passage 11 through portal S. By-pass 17 insures that an amount of oxygen sufficient for the patient's needs will be supplied to the inhalation passage.

As illustrated in Figs. 1, 5, and 6 a rotatable valve R is provided in portal S whereby during insufflation the passageway 12 will be cut off and oxygen be supplied both through the nozzle 16 and the by-pass 17 (Fig. 5), whereas during exhalation by-pass 17 will be closed and the gas exhausted from the patient's lung will flow upwardly through passage 12 into passageway 11 and will be vented through port 11p (Fig. 1), which is closed during insufflation by the upturned portion of the slide valve to be described. The means for actuating valve R is hereinafter described.

A slide valve having a horizontal portion 18 and a vertically extending flange portion 18f, is provided with the horizontal portion slideably seated in slideway 19 extending across passages 11 and 12 at right angles thereto, and with the flange portion 18f extending upwardly over the front exterior of the device. In the horizontal portion of slide valve 18 are ports 18a and 18b adapted to register with passageways 11 and 12 respectively for alternately opening and cutting off communication between passages 11 and 12 and the patient's lungs. Ports 18a and 18b are spaced so that only one of them may be in register with its passageway at a time, the port that is open being closed and the closed port opened on each reciprocation of the slide.

Upturned portion 18f of the slide valve is adapted to slide over ports 11p and 12p which extend horizontally through the front wall of the device and communicate respectively with the passageways 11 and 12. In the upturned portion 18f of the slide valve 18 is a port 18p, which at the end of each reciprocation of valve 18 is in register either with port 11p or 12p. During exhalation, when port 18p is in register with passageway 12, ports 18p and 11p will be in register, and port 12p will be closed; and during insufflation, when port 18a is in register with passageway 11, ports 18p and 12p will be in register and port 11p will be closed.

When rotary valve R is employed to close communication between passageways 11 and 12 during insufflation, port 12p is not required. In some cases, however, it is desirable to dilute the oxygen supplied to the patient, and in such cases the means for reciprocating valve R may be dis-

connected, and valve R employed as a stationary valve to close passage 17 while port 12p is employed as an air intake port during inhalation.

As illustrated herein the portion of inhalation 5 passageway 11 between the tip of the nozzle 16 and slide valve 18 is in the form of a Venturi tube, which serves, with the high speed jet of oxygen from nozzle 16, to create suction at portal S to draw the exhalation gases from passage 12 into 10 passageway 11 and expel them through ports 11p and 12p during exhalation (Fig. 6), or to draw air into passage 12 through ports 12p and 11p and thence into passageway 11 to be mixed with the oxygen, when valve R is not employed as a 15 reciprocating valve. The nozzle 16 may be screw threadedly fitted into the top of passageway 11 which is fashioned to receive it and has a bore 20 of very narrow diameter provided with a screen 21 positioned at its upper end to prevent particles of dust and dirt from clogging it. The screen 20 may be held in place by means of screw cap 22 threadedly engaged within the concavity provided therefor in the top of the nozzle 16. Intermediate the ends of the bore 20 but adjacent the 25 tip of the nozzle 16 an air chamber 23 is provided which communicates, through radially extending ports 24, with passage 11 opposite portal S. Gaseous fluids from passage 12 or 17 are drawn into the nozzle 16 through ports 24 and ejected through the tip of the nozzle, or drawn through the channel 25 surrounding the periphery of the reduced tip of nozzle 16, between the tip of the nozzle and the wall of the inhalation passageway 11.

Slide-valve 18 is reciprocated by movements of pressure sensitive member 42 induced as will be further explained by variations in pressure in my device corresponding with the pressure in the patient's lungs, transmitted through bell crank 31, pivoted to the body 10 of the device at 32, and its spring arm 30. After a predetermined degree of rotation of the bell crank 31 about its pivot in either direction, in a manner to be described, the spring arm 30 moves from engagement with one of a pair of permanent magnets 33a and 33b into engagement with the other of said permanent magnets and during the course of this movement engages one of the pins m and n projecting from the face of the slide valve 40 flange 18f thereby reciprocating the slide valve. The pins m and n are positioned on valve flange 18 so that arm 30 will not strike either of them when moving in either direction until it has entirely freed itself from the magnet with which 45 it was last engaged and has gained momentum, so that when the contact occurs the slide valve 18 will be moved sharply and positively the full distance required to open one of passageways 11 or 12 and close the other. The permanent 50 magnets are slideably mounted in slots 34 provided in bracket 35 secured on the front of the body portion 10 of my device, so that the distance between each of them and spring arm 30 and its pivot 32 may be adjusted. As illustrated 55 the bracket is a unitary member having outwardly extending flanges 36 inclined toward one another in the direction of pivot 32 and secured on the body portion 10 of the device by means of screws 37 extending through the lugs 38 on the bracket. If desired the flanges 36 may comprise 60 part of a continuous shield or cover extending over the ports 11p and 12p, the arm 30, and the permanent magnets 33a and 33b.

It will be noted that, as illustrated in Figure 2, 65 permanent magnet 33a is positioned somewhat

nearer pivot 32 than permanent magnet 33b. The pressure required to disengage spring arm 30 from permanent magnet 33a will therefore be less than is required to disengage it from permanent magnet 33b. Spring arm 30 is engaged with magnet 33a during exhalation and it will thus be seen that a lesser suction pressure will be exerted on the patient's lungs during exhalation than the positive pressure exerted during insufflation. Very satisfactory results are attained by selecting and positioning the parts of my device so that the contact between arm 30 and permanent magnet 33b will be broken when a positive pressure of 4 ounces per square inch is attained in the patient's lungs, and the contact between arm 30 and magnet 33a will be broken when a negative pressure of 3 ounces per square inch is developed in the patient's lungs.

Below slide valve 18 a small pressure equalizing by-pass is provided between passages 11 and 12. Opening from inhalation passage 11 below slide valve 18 is a passageway 40 communicating through conduit 41 and coupling 41a with the bellows 42 which is adapted to expand upwardly when gas under positive pressure is introduced therein and to deflate when the positive pressure is cut off and a negative pressure is communicated thereto. At the top of bellows 42 a pin 43 is provided which extends through arm 44 of bell crank 31 and has thereon two half spherical members 43a and 43b the spherical surfaces of which engage the opposite faces of arm 44. The arm 44 is thus engaged at a point and is capable of some rocking action during the periods of expansion and contraction of the bellows while the positive or negative pressure in the patient's lungs and in passages 11 and 12 below slide valve 18 are building up to the predetermined pressure necessary to move the bellows 42, bell crank 31 and spring arm 30 sufficiently to break the contact between spring arm 30 and whichever of the permanent magnets 33a or 33b by which it is engaged. Inflation and deflation of member 42 will of course rock bell crank 31 on its pivot accordingly and will tend to similarly move spring arm 30 but the latter being flexible will remain in fixed position, in contact with one or the other of the permanent magnets, until its torsional strain exceeds the attraction of the magnet with which it is in contact.

The rotary valve R extends through the body portion 10 of the device and as shown in Fig. 2 has the exterior arm or crank 50, which is slotted at 51 to receive pin 52 fixed on bell crank 31. Valve R will thus be rotated synchronously with bell crank 31 and therefore with the reciprocations of slide valve 18. If for the purpose of diluting the oxygen supply it is desired to draw air into the device through port 12p and mix it with the oxygen in passageway 11 during insufflation, this may be accomplished by placing valve R in the position indicated in Fig. 6 and the dotted position indicated in Fig. 2, and disengaging pin 52 from slot 51. To this end pin 52 is desirably provided with annular grooves 52a and 52b which cooperate with the spring detent 53 in securing the pin 52 in active or inactive position. In Fig. 7, pin 52 is illustrated in inactive position.

The ability of arm 30 to swing sharply from one magnet to the other is enhanced by spring 45 the upper end of which is attached to pin 46 projecting from the front face of the device near its top, and the lower end of which is se-

cured to pin 47 projecting from arm 30 near its lower end. It will be noted that the force exerted by spring 45 will be greatest when arm 30 is midway between the extremities of its arc of movement and will thus accelerate the pendulum-like movement of arm 30 after passing this point in either direction.

Positioned in inhalation passage 11 adjacent passage 40 leading to the pressure responsive member 42 is a conical valve 60, Figures 1, 3 and 4, which serves to close conduit 40 and passage 11, and open passageways 61 and 62 leading to and from an auxiliary gas reservoir T, indicated in dotted lines in Figs. 1 and 3 for the purpose of providing an even supply of oxygen during inhalation, when it is desired to use the device as a simple inhalator instead of as a resuscitator. The passageways 61 and 62 communicate with conduits 63 and 66 respectively leading to the inlet and outlet ports 64 and 65 of said auxiliary gas reservoir by means of annular grooves 68 and 68' provided in conical valve 60 (see Fig. 4). At some convenient place, such as the connection to the said auxiliary gas reservoir T, an intake valve 64' is also preferably provided, which opens to admit atmospheric air if for any reason the reservoir becomes exhausted and the amount of oxygen being supplied to the patient through the device is insufficient.

It will be readily understood that when gaseous fluid is not flowing into or out of the member 42 it will be stationary and consequently slide valve 18 and valve R will remain stationary and in order to change the device from use as a resuscitator to a simple inhalator it is only necessary to set valve R to the position shown in Fig. 1, and turn valve 60 in accordance with the marking on the lower face of the device (see Fig. 2). As shown, valve 60 is journalled in a tapered seat 60' which intersects the passage 11 at right angles. A handle 72 is secured on offset portion 71 of valve 60 and the nut 73 is secured on another reduced portion of the valve at its rear end and abuts against spring 74 intermediate it and the rear wall 10 of the device to seat and seal the valve 60 properly while permitting its free rotation. Valve 60 is partly cut away at 67 forming a concavity in communication with passage 11 (Fig. 1), and from this cut away portion, a passage 67' extends to the periphery of the valve and is brought into alignment with conduit 40 while the device is being used as a resuscitator. Adjacent its rear end, valve 60 has two partial annular grooves or passages 68 and 68' communicating between inlet channel 61 and outlet channel 62 with the respective inlet and outlet conduits 63 and 66 leading to and from the inlet and outlet ports 64 and 65 of auxiliary gas reservoir T while the device is being used as an inhalator.

When the device is used simply as an inhalator, exhalation will be accomplished through a one-way valve in the mask (see Fig. 2) with which my device communicates. While the device is used as a resuscitator this valve is not required but is turned to operative position when it is desired to use the device as an inhalator.

When the device is used as a resuscitator the handle 72, Fig. 2 will be turned to the right and valve 60 will accordingly be in the position shown in Fig. 1, whereby, during inhalation, gas will flow through passage 11 directly to the patient's lungs and also through conduits 40 and 41 into

bellows 42 to operate crank arm 31 causing reciprocations of the spring arm 30 as the pressures in bellows 42 is increased during inhalation or decreased during exhalation. In corresponding movements the valve 19 will alternately open and close inhalation passage 11 and exhalation passage 12. The inhalation passage 11 communicates with conduit 13' (shown in Fig. 2) leading to mask M which is placed over the patient's face and conduit 14' leading from the said mask communicates with exhalation passage 12.

When the device is used as a simple respirator the handle 12, shown in Fig. 2, is positioned so that conical valve 60 will be in the position indicated in Fig. 4 thereby closing communication through conduits 40 and 41 to the bellows, which is utilized during resuscitation to cause crank 31 and therefore spring arm 30 to reciprocate thus operating slide valve 19 and causing inhalation and exhalation pressures to be built up alternately, but is not needed while the device is used as a simple respirator. Besides cutting off bellows 42, conical valve 60 closes the main passage through the lower portion of passageway 11 but opens an alternative passage which passes through the auxiliary gas reservoir T. The use of this auxiliary gas supply during respiration insures a reserve supply and therefor an even supply of oxygen irrespective of the evenness of the flow in the upper portion of passageway 11.

While the device is used as a respirator the gas from the oxygen tank passes through passage 11, port 61, annular groove 68 (Fig. 3) in conical valve 60, conduit 63 to the inlet 64 of auxiliary gas reservoir T and from the gas reservoir through outlet 65 of said gas reservoir T, conduit 66, and annular groove 68' of conical valve 60 and outlet port 62 into the lower end of passage 11, and through conduit 13' to the mask M, shown in Fig. 2, from which it is inhaled by the patient. Gases exhaled by the patient do not pass through the conduit 14' and outlet passageway 12 but are exhausted directly from the mask M through the valve illustrated on the mask and identified as "Exhalation valve."

What I claim is:

1. A resuscitation device comprising an inhalation passage adapted to be connected intermediate a source of oxygen supply and a patient's lungs, an exhaust passage adapted to be connected to the patient's lungs and an intermediate portion of the inlet passage, valve means positioned below the point of intercommunication between said passages for simultaneously opening one of said passages and closing the other, a pressure responsive member, a conduit leading from said inhalation passage below the said reciprocable valve to the said member, said reciprocable valve having a plurality of spaced contact members, a pivoted arm adapted to engage one of said contacts when it is travelling in one direction and the other contact when it is travelling in the other direction, means connected between said pressure responsive member and said pivoted arm for actuating said arm, and means positioned adjacent respective ends of the path of said pivoted arm adapted to engage said arm and hold it until a predetermined opposing pressure is exerted on the arm.

2. An inhalation and resuscitation device comprising an inhalation passage adapted to be connected intermediate a source of oxygen supply and a patient's lungs, an exhaust passage adapted to be connected to the patient's lungs and an intermediate portion of the inlet passage, an aux-

iliary inlet passage opening into the inhalation passage at its point of junction with the exhaust passage, valve means for alternately cutting off communication between said inhalation passage and said exhaust passage or said auxiliary inlet, and a reciprocable valve for closing either said inhalation passage or said exhaust passage and simultaneously opening the other passage when a predetermined positive or negative pressure has been built up therein, a duct communicating between said inhalation and exhalation passages below the said reciprocable valve, a pressure responsive member, a conduit connecting said member with the inhalation passageway below the said reciprocable valve, means controlled by the movement of said member for reciprocating both of said valves in synchronism, and means for disconnecting said inhalation passageway and the pressure responsive member and thereby preventing reciprocation of said valve so that the device may be employed as an inhalator.

3. An inhalation and resuscitation device comprising an inhalation passage adapted to be connected intermediate a source of oxygen supply and a patient's lungs, an exhaust passage adapted to be connected to the patient's lungs and an intermediate portion of the inlet passage, an auxiliary inlet passage opening into the inhalation passage at its point of junction with the exhaust passage, valve means for alternately cutting off communication between said inhalation passage and said exhaust passage or said auxiliary inlet, and a reciprocable valve for closing either said inhalation passage or said exhaust passage and simultaneously opening the other passage when a predetermined positive or negative pressure has been built up therein, a duct communicating between said inhalation and exhalation passages below the said reciprocable valve, a pressure responsive member, a conduit connecting said member with the inhalation passageway below the said reciprocable valve, means controlled by the movement of said member for reciprocating both of said valves in synchronism, and means for disconnecting said inhalation passageway and the pressure responsive member, thereby preventing reciprocation of said valve so that the device may be employed as an inhalator, and simultaneously connecting said passage with the conduits of said gas reservoir.

4. A resuscitation device comprising an inhalation passage adapted to be connected intermediate a source of oxygen supply and a patient's lungs, an exhaust passage adapted to be connected to the patient's lungs and an intermediate portion of the inlet passage, an auxiliary inlet passage opening into the inhalation passage at its point of junction with the exhaust passage, valve means for alternately cutting off communication between said inhalation passage and said exhaust passage or said auxiliary inlet, and valve means for closing either said inhalation passage or said exhaust passage and simultaneously opening the other passage when a predetermined positive or negative pressure has been built up therein, a duct communicating between said inhalation and exhalation passages below the said valve, a pressure responsive member, a conduit connecting said member with one of said passageways below the said valve, and means controlled by the movement of said member for reciprocating both of said valves in synchronism and means

positioned at the respective ends of the path of travel of said pivoted member to engage it with a predetermined force.

5. A resuscitation device comprising an inhalation passage adapted to be connected intermediate a source of oxygen supply and a patient's lungs, an exhaust passage adapted to be connected to the patient's lungs and an intermediate portion of the inlet passage, an auxiliary inlet passage opening into the inhalation passage at its point of junction with the exhaust passage, valve means for alternately cutting off communication between said inhalation passage and said exhaust passage or said auxiliary inlet, and valve means for closing either said inhalation passage or said exhaust passage and simultaneously opening the other passage when a predetermined positive or negative pressure has been built up therein, a duct communicating between said inhalation and exhalation passages below the said valve, a pressure responsive member, a conduit connecting said member with one of said passageways below the said valve, and means controlled by the movement of said member for reciprocating both of said valves in synchronism, an intake port in said exhaust passage, a vent port in said inhalation passage, and means associated with said reciprocable valve for opening the air intake port when the exhaust port is closed and for closing the vent port when the inhalation passage is open.

6. In a device for mechanically insufflating and deflating a patient's lungs including an inhalation channel and an exhalation channel adapted to be connected between a source of oxygen and the patient's lungs, a valve for simultaneously opening one of said channels and closing the other, means controlled by the gas pressure within the device and the patient's lungs for actuating said valve including a pivoted pendulum-like arm, means for reciprocating said arm, a pair of magnets positioned and adapted respectively to engage said arm with a predetermined force at the extremities of its travel, and means for operatively engaging said valve and arm during the latter's travel in either direction.

7. A device for mechanically insufflating and deflating a patient's lungs including an inhalation channel and an exhalation channel adapted to be connected between a source of oxygen and the patient's lungs, a valve for simultaneously opening one of said channels and closing the other, means controlled by gas pressure within the channel and the patient's lungs for actuating said valve including a pivoted pendulum-like arm, a pair of magnets positioned and adapted to engage said arm with a predetermined force at the extremities of its travel, means for operatively engaging said valve and arm during the latter's travel in either direction, a valve in said exhalation channel, and means movable with said arm for operating said valve in synchronism with said first mentioned valve.

8. A device adapted to alternately create positive and negative pressures in a patient's lungs or alternatively to supply gas to be inhaled and exhaled by the patient, comprising, an inhalation passage adapted to be connected intermediate a source of gas supply and a patient's lungs, an exhaust passage adapted to be connected intermediate a patient's lungs and said inhalation passage, a slide valve extending transversely of said inhalation and exhaust passages having a port therein adapted to register alternately with said passages, a vent in the wall of each of said

passages, means for operating said valve member, and means actuated by said valve for closing the vent in the passage with which the port in the said slide valve is in register.

5 9. A device adapted to alternately create positive and negative pressures in a patient's lungs or alternatively to supply gas to be inhaled and exhaled by the patient, comprising, an inhalation passage adapted to be connected intermediate a source of gas supply and a patient's lungs, an exhaust passage adapted to be connected intermediate a patient's lungs and said inhalation passage, a slide valve extending transversely of said inhalation and exhaust passages having a port therein adapted to register alternately with said passages, a vent in the wall of each of said passages, and means actuated by said valve for closing the vent in the passage with which the port in the said slide valve is in register, a pressure responsive member, a conduit connecting said pressure member with said inhalation passage, and means controlled by the movement of said pressure member for reciprocating said slide valve.

10 10. A device adapted to alternately create positive and negative pressures in a patient's lungs or alternatively to supply gas to be inhaled and exhaled by the patient, comprising, an inhalation passage adapted to be connected intermediate a source of gas supply and a patient's lungs, an exhaust passage adapted to be connected intermediate a patient's lungs and said inhalation passage, valve means for simultaneously opening one of said passages and closing the other, a pressure responsive member, a conduit connecting said pressure responsive member with said inhalation passage, and means controlled by the movement of said pressure responsive member for actuating said valve means, and a duct communicating between said inhalation and exhalation passages, said duct and said conduit connecting the pressure member with the inhalation passage being located on the same side of said valve means.

15 11. A device adapted to alternately create positive and negative pressures in a patient's lungs or alternatively to supply gas to be inhaled and exhaled by a patient, comprising, an inhalation passage adapted to be connected intermediate a source of gas supply and a patient's lungs, an exhaust passage adapted to be connected intermediate a patient's lungs and said inhalation passage, valve means for simultaneously opening one of said passages and closing the other, a pressure responsive member, a conduit connecting said pressure member with said inhalation passage, and means controlled by the movement of said pressure member for reciprocating said slide valve, a chamber for storing oxygen, a conduit connecting said inhalation passage to said chamber, and valve means for alternately closing one of said conduits and opening the other.

20 12. A device adapted to alternately create positive and negative pressures in a patient's lungs or alternatively to supply gas to be inhaled and exhaled by the patient, comprising, an inhalation passage adapted to be connected intermediate a source of gas supply and a patient's lungs, an exhaust passage adapted to be connected intermediate a patient's lungs and said inhalation passage, a slide valve extending transversely of said inhalation and exhaust passages having a port therein adapted to register alternately with said passages, a vent in the wall of each of said passages, and means actuated by said valve for

25 30 35 40 45 50 55 60 65 70 75

closing the vent in the passage with which the port in the said slide valve is in register, and an additional inlet for supplying gas, opening into the inhalation passage at its point of junction with the exhaust passage, and valve means for alternately connecting said additional inlet or said exhaust passage to said inhalation passage.

13. A device adapted to alternately create positive and negative pressures in a patient's lungs or alternatively to supply gas to be inhaled and exhaled by a patient, comprising, an inhalation passage adapted to be connected intermediate a source of gas supply and a patient's lungs, an exhaust passage adapted to be connected intermediate a patient's lungs and said inhalation passage, valve means for simultaneously opening

one of said passages and closing the other, a pressure responsive member, a conduit connecting said pressure member with said inhalation passage, and means controlled by the movement of 5 said pressure member for reciprocating said slide valve, a chamber for storing oxygen, a conduit connecting said inhalation passage to said chamber, and valve means for alternately closing one of said conduits and opening the other, an additional inlet for supplying gas opening into said inhalation passage at its point of junction with the exhaust passage, and valve means for alternately connecting the inhalation passage to said auxiliary inlet and to said exhaust passage.
